UNITED STATES PATENT OFFICE.

DAVID G. MORGAN, OF SAN FRANCISCO, CALIFORNIA.

MULTIPLE-NUT LOCK.

1,142,192.

Specification of Letters Patent. Patented June 8, 1915.

Application filed June 29, 1914. Serial No. 847,843.

To all whom it may concern:

Be it known that I, DAVID G. MORGAN, a citizen of the United States, residing in the city and county of San Francisco and State 5 of California, have invented new and useful Improvements in Multiple-Nut Locks, of which the following is a specification.

This invention relates to nut locks and pertains especially to a lock for nuts or clips 0 of automobiles, fish plates and wherever there are usually a pair of adjacent nuts and it may be desired from time to time quickly to remove these nuts.

The object of the invention is to provide a 5 thoroughly reliable, practicable and inexpensive lock for nuts, as above described.

It is a further object to provide a nut lock devoid of fragile parts and which is particularly designed to eliminate the machining, 0 altering or specially forming the nut or bolt; and therefore to provide a nut lock which is readily adaptable for use with standard parts and without the application of any tools or special appliances and without requiring any intrinsic alterations of structure.

The invention consists of the parts and the combination and construction of parts as hereinafter more fully described and 0 claimed, having reference to the accompanying drawings, in which—

Figure 1 is a perspective of the lock applied to a clip. Fig. 2 is a perspective of the lock detached and separated.

5 A is an ordinary U-shaped clip embracing a part or parts 2, such as an axle and spring on an automobile.

The nut lock comprises a coupler plate 3 perforated to pass over the threaded ends 4 0 of the clip A and having approximately midway of its ends on its flat side an outwardly opening U-shaped spring clip 5 to form a substantially dove-tail spring clamp and seat for holding a locking bar 6; the clamp-

ing clip 5 being riveted, or otherwise fixed 45 to the coupler plate 3 so as to provide the convergent spring arms forming the dove-tail.

The locking bar 6 has squared ends and is of a length just to fit between the nuts 7 50 when two of their adjacent sides are parallel. Bar 6 is preferably trapezoidal in cross-section, so that its outwardly convergent side edges 8, will, when the bar is pressed in between the spring arms of the 55 clamp clip 5, be received into the dove-tail shaped space inclosed by clip 5 and the bar thus securely held in place without other means. Any tendency to turning by the nuts 7 simply operates to hold the locking bar 6 60 the tighter. A screw driver serves to pry the lock bar out of the clip and from between the two nuts whenever it is desired to dismantle the parts.

Having thus described my invention, what 65 I claim and desire to secure by Letters Patent is—

A lock for the nuts of a pair of bolts consisting of a plate apertured at its ends to receive the respective bolts, a U-shaped 70 spring clip formed independent of the plate and having its base riveted to the outer side face of the plate at a point central of the length of the plate and a locking bar engageable with the clip and at its ends with 75 the nuts, each of the ends of said bar being held in spaced relation to the outer side face of the plate by the said base of the clip whereby to allow an instrument to be inserted in said space at either end of the bar and 80 the bar thereby disengaged from the clip.

In testimony whereof I have hereunto set my hand in the presence of two subscribing witnesses.

DAVID G. MORGAN.
